United States Patent Office

Des. 214,555
Patented July 1, 1969

214,555

CONTAINER FOR STORING AND INTERMIXING DENTAL AMALGAM MATERIALS

Pierre Allet-Coche, Paris, France, assignor to Jean-Jacques
Goupil, Cachan, France

Filed Feb. 6, 1968, Ser. No. 10,460

Term of patent 14 years

Int. Cl. D9—04

U.S. Cl. D9—216

FIG. 1

FIG. 2

FIG. 3

FIG. 4

FIG. 1 is a perspective view of a container for storing and intermixing dental amalgam materials, showing my new design;

FIG. 2 is an elevational view;

FIG. 3 is a top plan view; and

FIG. 4 is a bottom plan view thereof.

I claim:

The ornamental design for a container for storing and intermixing dental amalgam materials, as shown.
